(57) **CLAIM**

I claim the ornamental design for a laundry knob, as shown and described.

DESCRIPTION

FIG. 1 is a first top perspective view of the laundry knob of the present invention;

FIG. 2 is a typical side elevation view of the laundry knob of the present invention;

FIG. 3 is a top plan view of the laundry knob of the present invention;

FIG. 4 is a bottom plan view of the laundry knob of the present invention; and,

FIG. 5 is a second top perspective view of the laundry knob of the present invention.

The broken lines in the figures are for contextual purposes or show the environment and form no part of the claimed design.

1 Claim, 5 Drawing Sheets
